UNITED STATES PATENT OFFICE.

WILLIAM O. DWYER, OF PITTSFIELD, MASSACHUSETTS, ASSIGNOR TO GENERAL ELECTRIC COMPANY, A CORPORATION OF NEW YORK.

CASING FOR ELECTRICAL APPARATUS.

1,425,843.

Specification of Letters Patent. Patented Aug. 15, 1922.

Application filed October 22, 1920. Serial No. 418,842.

To all whom it may concern:

Be it known that I, WILLIAM O. DWYER, a subject of the King of Great Britain, residing at Pittsfield, in the county of Berkshire, State of Massachusetts, have invented certain new and useful Improvements in Casings for Electrical Apparatus, of which the following is a specification.

My invention relates to casings for electrical apparatus submerged in oil, such as transformers and the like.

In electrical apparatus of this type, it has become the practice, particularly for large units and for high voltages, to fill the main casing completely with oil, since the exclusion of the air therefrom has many advantages in addition to the reduction in the size of the tank or casing required. Preeminent among such advantages is the avoidance of sludging or rapid oxidizing of the oil and the general exclusion of moisture from the oil in the main casing which tends to decrease the dielectric strength of the oil. This practice has led to the use of auxiliary tanks or casings, sometimes called "conservators" in conjunction with the main tank or casing in order to accommodate the expansion and contraction of the oil due to changes in the load or other causes.

The general object of my invention is accordingly to provide an improved arrangement of parts, where such conservators are used, which will be economical, efficient and readily manufactured, and in which there is little likelihood of the moisture collected therein being drawn therefrom over into the main tank or casing.

In accomplishing this object the auxiliary tank is secured and connected to the main tank in a manner providing free intercommunication between the oil contents of the two tanks and for the collection and removal of the moisture at a point independent of and preferably remote from the communicating connection.

Further objects and advantages of my invention will appear, and a more complete understanding thereof may be had from the following detailed description taken in conjunction with the accompanying drawings in which:

Fig. 1 is a view, mainly in side elevation, of a casing for a transformer equipped with my invention; Fig. 2 is a fragmentary view 55 of a portion of the device shown in Fig. 1

taken in a plane at right angles to the plane of Fig. 1; and Fig. 3 shows a modified embodiment of my invention.

Referring now to Fig. 1 of the drawings, 10 denotes a tank or casing, here shown as provided with external radiators 11, which tank is adapted to house the transformer or other electrical apparatus whose main cooling medium is the oil or other insulating fluid in the tank.

The radiators 11 are shown as attached to the tank or casing 10 by means of top and bottom pipe couplings or elbows 12 and 13, permitting a ready circulation of the oil therethrough and also providing a ready means for detachment. Tanks thus equipped are generally mounted on portable bases, such as shown at 14.

The auxiliary tank or "conservator", for accommodating the expansion and contraction of the oil filling the main tank 10, is shown at 15 and is supported adjacent the main tank by a suitable frame work 16 attached thereto. This auxiliary tank communicates with the main tank through the pipe connection 20 which preferably contains a valve, as shown at 21, for a purpose hereinafter more fully pointed out. The pipe 20 leads preferably from a point near the bottom of auxiliary tank 15 and enters tank 10 substantially at the highest point to which the oil content thereof extends. The point of entrance here shown is in the side of an upwardly projecting boss 22 formed on the cover 23 of tank 10 as shown most clearly in Fig. 2. This boss serves as a convenient means for securing the escape pipe 24 thereto, over the upper end of which pipe is secured a thin diaphragm 25. This diaphragm may be of any suitable material, for instance a metallic diaphragm which has been treated to resist corrosion and is proportioned so as to rupture under excessive gas pressure, and hence serves as an emergency exit for gases which may be generated within the tank 10 by the occurrence of a transient disturbance such as a short circuit.

The auxiliary tank, in accordance with my invention, is equipped with a so-called "breather" as shown at 30, in Fig. 1, which comprises a chamber 31 open at its lower end to the atmosphere and containing a suitable dehydrating agent such as calcium chloride for absorbing moisture from the air passing therethrough. The upper end of

the chamber 31 communicates with the auxiliary tank 15 by means of a pipe 32 which enters the tank through the bottom of a depending portion or 'drum' 33 formed on the auxiliary tank. The pipe 32 projects upwardly and reaches substantially to the top of the auxiliary tank as shown. The depending drum 33 is designed to serve as a sump in which to collect the water or moisture which has gotten into the oil. Accordingly, it is desirable so to locate this drum that there will be little likelihood of the water or moisture collecting here getting into the main tank. To this end the drum 33 is located independently of and below the entrance of pipe 20 into the auxiliary tank 15. This location in the bottom of the auxiliary tank 15 is also preferably somewhat remote from the entrance of pipe 20; hence the position adjacent one end of the auxiliary tank as shown.

In order that the water or moisture which collects in the drum 33 may be readily drained off, preferably at regular intervals, it is provided with a draw-off cock 34. In addition to the "breather" this tank is provided with a safety valve 35 which is clearly shown in Fig. 2, and is adapted to permit of a more rapid egress of gases than the "breather" will accommodate.

The operation of this form of my invention is as follows: When the main tank 10 and the auxiliary tank 15 are properly filled with oil and communication is established through pipe 20, normal expansion and contraction of the oil, due to changes in the load or in the ambient temperature, are accommodated by the passage of air or breathing through the "breather" together with a rise and fall of the oil head in the auxiliary tank; such head being preferably visually ascertained by means of a gauge glass as shown at 36. Abnormally rapid expansion or the generation of gas within the main tank on the other hand is permitted to spend itself harmlessly through the exits afforded by the safety valve 35 and the escape pipe 24.

When it is desired to remove from the tank a bushing, such as shown at 37, or to change the tap connections, it is not necessary first to remove the oil from the auxiliary tank 15 as would be the case were the communicating pipe 20 not provided with a valve 21 as shown. In the case illustrated, however, all that is necessary is to close this valve, thereby confining the excess oil to the auxiliary tank while the bushing is being removed or while an opening into the main tank is otherwise open.

In the modified form shown in Fig. 3, the main tank 40 is illustrated as equipped with auxiliary tank 41 and communicates therewith through pipe connection 42 which is not provided with a shut-off valve of any

kind. The auxiliary tank 41 has a depending sump 43 through the bottom of which enters the "breather" pipe 44 from the dehydrating chamber 45 of the "breather" proper. The sump 43 is shown as provided with a draw-off cock 46.

The operation of this form of my invention will readily be understood from the description of the operation given above.

Having now described what is at present the best means known to me for carrying out an embodiment of my invention, I would have it understood that such means are merely illustrative and that I do not mean to be limited thereby to the exact details shown nor restricted in the choice of recognized equivalents except as defined in my claims hereunto appended.

What I claim as new and desire to secure by Letters Patent of the United States, is:

1. The combination with a main casing for electrical apparatus, of an auxiliary casing secured to the main casing and provided with a passage establishing communication with the main casing, and an insulating liquid within said main casing and extending through said passage into the auxiliary casing, said auxiliary casing being provided with a depending portion independent of said passage and located below the entrance of said passage thereinto.

2. The combination with a main casing for electrical apparatus, of an auxiliary casing secured to the main casing and provided with a passage establishing communication with the main casing, an insulating liquid within said main casing and extending through said passage into the auxiliary casing, said auxiliary casing being provided with a depending portion independent of said passage and below its entrance into the auxiliary casing, and a pipe opening to the atmosphere extending up through said depending portion into the auxiliary casing.

3. The combination with a main casing for electrical apparatus, of an auxiliary casing secured to the main casing and provided with a passage establishing communication with the main casing, and an insulating liquid within said main casing and extending through said passage into the auxiliary casing, said auxiliary casing being provided with a depending portion having a drain, said depending portion being independent of said passage and located below its entrance into the auxiliary casing, and a breather pipe entering said depending portion and extending up into the auxiliary casing.

4. The combination with a main casing for electrical apparatus adapted to contain a fluid insulating medium, of an auxiliary casing secured to the main casing and provided with a passage establishing communication with the main casing, said auxiliary casing being formed with a depending portion in-

dependent of said passage and provided with a drain, and a shut-off valve located in said passage.

5. The combination with a main casing for electrical apparatus adapted to contain a fluid insulating medium, of an auxiliary casing secured to the main casing and provided with a passage establishing communication with the main casing, said auxiliary casing 10 being formed with a depending portion independent of said passage, located below its entrance into the auxiliary casing, and provided with a drain, a pipe communicating with the atmosphere entering said depending portion and extending up to a point adjacent the top of the auxiliary casing, and a shut-off valve in said passage.

6. The combination with a main casing for electrical apparatus adapted to contain a fluid insulating medium, of an auxiliary casing secured to the main casing and provided with a passage establishing communication with the main casing, said auxiliary casing being formed with a depending portion 20

independent of said passage located 25 below its entrance into the auxiliary casing and provided with a drain, a breather pipe entering said depending portion and extending up to a point adjacent the top of said auxiliary casing, and a shut-off valve 30 in said passage.

7. The combination with a main casing for electrical apparatus adapted to contain a fluid insulating medium, of an auxiliary casing secured to the main casing and provided with a passage establishing communication with the main casing, said auxiliary casing being formed with a depending portion independent of said passage located below its entrance into the auxiliary casing and having 35 a drain, a breather pipe entering said auxiliary casing through said depending portion, and means accommodating excessive expansion from said main casing.

In witness whereof, I have hereunto set 40 my hand this nineteenth day of October, 1920.

WILLIAM O. DWYER.
